FINGER PICK

Ylan K. Kealoha, New York, N. Y.

Application April 16, 1932, Serial No. 605,631

4 Claims. (Cl. 84—322)

The present invention relates to new and useful improvements in finger picks for use in the playing of stringed instruments.

Devices of this character with which I am familiar have several disadvantages. Such devices which I have used are not possessed of sufficient resiliency to produce the best results as pertains to tone quality and volume.

Another disadvantage inherent in such devices as generally constructed is the manner in which these devices are attached to the fingers in use, they being extremely difficult to maintain in proper position on the finger under severe conditions of use.

It is an object of the present invention so to construct a finger pick that the pick in its engagement and disengagement with the strings of the instrument will produce a clear resonant tone of the proper volume and without harsh tones so commonly apparent when picks as generally constructed are employed.

A further object of the invention is to provide a new and novel form of attaching band which will be comfortable during the playing operation, and which will at all times maintain the finger pick in proper position upon the finger even under severe conditions of use.

With the above and other objects in view, reference is had to the accompanying drawing, in which:

Figure 1 is a perspective view illustrating a pick constructed in accordance with one form of the present invention.

Figure 2 is a view in side elevation thereof showing the pick attached to the finger of a user,

Figure 3 is a top plan view showing the pick in operating position.

Figure 4 is a bottom plan view thereof,

Figure 5 is a longitudinal sectional view taken in perspective,

Figure 6 is a top plan view of the blank from which the pick is formed,

Figure 7 is a bottom perspective view of the pick, the pick being of slightly modified form,

Figure 8 is a bottom plan view of that form of pick illustrated in Figure 7, and

Figure 9 is a longitudinal sectional view.

In the illustrated embodiment of the invention, the pick comprises a main body portion 10 which terminates in a picking tip 11 at one end. At the other end of the main body portion there is a finger encircling band 15.

In the present illustration, the body portion is shown in two different forms, one of which forms

is illustrated in Figures 1 to 6 and Figure 9, the other form being illustrated in Figures 7 and 8.

In that form of the invention illustrated in Figures 1 to 6 inclusive, and Figure 9, the main body portion 10 is narrower than in that form of the invention illustrated in Figure 8. In each form, however, the body portion 10 has curved side edges 12, and these side edges curve from a point approximately at the center of the body portion toward the picking end thereof at which they terminate in the picking tip 11. In both forms, the body portion also is of slightly disked form. This construction provides a curved outer face for the pick and this construction together with the curved side edges 12 of the body portion 15 insures such co-action between the body portion and the string struck or picked thereby, as to at all times, lead the string to the picking point and thus insure proper action of the pick upon the string.

The picking tip 11 is of a comparatively rigid nature, and this rigidity is obtained by thickening the material from which the body portion is formed as indicated at 14 in the drawing. This thickened tip may be provided by the adding of material at this point, or it may be formed by cutting away a portion of the material from which the body portion is formed in order that said body portion will be thinner than the picking tip and thus give considerable rigidity to the picking tip. The thickened portion 14 may be of any desired shape, but I prefer to provide this thickened portion in the form of a lug by the addition of a small amount of material immediately behind the picking point.

By reference to the drawing, it will be noted that the body portion 10 is longitudinally curved in an arc substantially conforming to the curvature of the end of a human finger and the body portion is of such length that the picking tip 11 thereof will be positioned in a plane above the top line of the finger in use, thus permitting of free insertion and withdrawal of the picking tip between strings of an instrument without interference with the strings.

The retaining band 15 consists of two wing-like portions 16 which project from the rear end of the body portion 10 and are connected thereto by a relatively narrow portion 17. By reference to Figure 6 it will be noted that the wing portions 50 are curved in such a manner that when they are bent to form the retaining band 15, the free ends thereof designated 18 in the drawing will extend forwardly in the direction of the picking point to a point where they overlie the nail of the finger to 55

- which the pick is attached as best illustrated in the plan view in Figure 3. The curvature of these wing-like extensions is such that as best illustrated in Figures 2 and 4 of the drawing, they pass in a rearward direction immediately they leave the body portion and then turn abruptly to a forward direction until their free ends overlie the nail of the finger at a point well in advance of the first knuckle thereof.
- 10 This construction of securing band has two distinct advantages. First, it provides a circular rear end for the body portion as indicated at 29 in the drawing which, when pressure is applied to the body portion by the finger, causes distension of the finger as indicated at 21 in Figure 2 to aid in maintaining the pick in proper position. Second, it throws the point of contact of the retaining band and the finger well forward of the first knuckle of the finger, thereby giving freedom of action to said knuckle.
- 15 The reference character 30 indicates a reinforcing rib which extends longitudinally of the body portion 10 of the pick. This reinforcing rib 30 is preferably punched from the body portion and 20 extends longitudinally forwardly from a point 31 closely adjacent the relatively narrow neck portion of the body portion to a point substantially central of the ends of the body portion.
- 25 This reinforcing rib provides rigidity or stiffness to this particular area of the body portion and provides a relatively high degree of resiliency in that area of the body portion of the pick which lies between the forward end of this rib and the picking tip of the pick and thus insures proper 30 action of the picking tip relative to the string which it engages.
- 30 The pick functions in the following manner: The finger is passed into the retaining band and the wing portions which form this band may either be spread or contracted to the proper point 35 so that the pick will comfortably fit the finger.
- 35 This position of the pick is best illustrated in Figure 2 of the drawing and by examination of said figure, it will be noted that the picking tip 40 of the pick is spaced from the end of the finger and projects to a point above the plane of the top thereof. If now pressure is applied to the picking tip 41, as in the picking of one or more strings of a musical instrument the body 45 portion of the pick flexes at that portion forward of the reinforcing bead 30 causing the string to lead to the picking tip 41 which being reinforced gives the proper action to the string to produce the proper tone quality as the string 50 clears the picking point. The pressure of the finger upon the body portion of the pick causes distension of the finger at the rear of the retaining band as indicated at 21 and in front of the retaining band as at 35 in the drawing and thus 55 prevents shifting of the pick upon the finger and insures its proper position at all times. Furthermore, pressure of the finger upon the body portion of the pick causes the retaining band 15 to rock forwardly so that the free ends 18 thereof 60 transmit pressure to the finger nail and do away with all binding on the finger proper and its attendant discomfort. Also, this rocking forward

of the retaining band still further insures freedom of action of the first knuckle of the finger upon which the pick is mounted.

That form of the invention illustrated in Figure 8 of the drawing is substantially the same in every respect as that of the form heretofore described, except that in this form of the invention, the body portion is slightly wider and the curve of the side edges thereof is less abrupt as is evident from the drawing and this construction provides a pick especially adapted for use upon the second finger as distinguished from the other form which is especially adapted for use upon the index finger.

From the foregoing, it will be readily apparent to one skilled in the use of picks of the general type herein disclosed, that the present invention provides a new and novel pick which is highly efficient in operation and which will maintain its proper position under operating conditions.

Having thus described the invention, what is claimed as new, and what it is desired to secure by Letters Patent of the United States, is:

1. A pick for stringed musical instruments comprising a body portion terminating at one end in a picking point, and a securing band for retaining said pick in operative position upon the finger of a user, said securing band comprising two wing extensions having their free ends curved forwardly, each wing extension being connected to the body portion whereby to provide resiliency between the body portion and the securing band.

2. A pick for stringed musical instruments comprising a body portion terminating at one end in a picking point, and a securing band for retaining said pick in operative position upon the finger of a user, said securing band comprising two wing extensions having their free ends curved forwardly, each wing extension being connected to the body portion by a relatively narrow portion whereby to provide resiliency between the body portion and the securing band, and a reinforcing rib extending longitudinally of the body portion from a point immediately forward of the juncture of the wings with the body portion.

3. A pick for stringed musical instruments, comprising a body portion terminating at one end in a picking-point and a securing band for retaining said pick in operative position upon the finger of the user, said securing band comprising two wing extensions connected to the body portion by relatively narrow portions and having substantial portions of their free ends curved forwardly into overlapping relation at a point which will overlie the finger nail, when the pick is in position for use.

4. A pick for stringed musical instruments comprising a main body portion, terminating at one end in a picking-point and a securing band for retaining said pick in operative position upon a finger of the user, said securing band comprising two winged extensions, having their free ends curved forwardly into overlapping relation at a point which will overlie the finger nail, when the pick is in position for use.

YLAN K. KEALOHA.
